(57) **CLAIM**

The ornamental design for a motorcycle or replica thereof as shown and described.

DESCRIPTION

FIG. 1 is a top, front and left side perspective view of a motorcycle or replica thereof showing our new design;

FIG. 2 is a top, rear and left side perspective view thereof;

FIG. 3 is a bottom, front and left side perspective view thereof;

FIG. 4 is a bottom, front and right side perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines depict portions of the motorcycle or replica thereof that form no part of the claimed design.

1 Claim, 10 Drawing Sheets
